EMBROIDERED FABRIC FOR PILLOW CASES OR THE LIKE

Edwin I. Cohen, New York, N. Y.

Application September 16, 1953, Serial No. 26,825

Term of patent 3½ years

(Cl. D3—9)

To all whom it may concern:

Be it known that I, Edwin I. Cohen, a citizen of the United States of America, residing in the city of New York, county of New York, and State of New York, have invented a new, original, and ornamental Design for an Embroidered Fabric for Pillow Cases or the Like, of which the following is a specification, reference being had to the accompanying drawing, forming part thereof, wherein,

The single figure of the drawing is a plan view of an embroidered fabric for pillow cases or the like, showing my new design.

The essential features of the design reside in the portions shown in solid black lines.

I claim:

The ornamental design for an embroidered fabric for pillow cases or the like, substantially as shown and described.
